UNITED STATES PATENT OFFICE.

EUGENE W. SKINNER, OF FULTON, NEW YORK, ASSIGNOR TO OSWEGO FALLS CORPORATION, OF FULTON, NEW YORK, A CORPORATION OF NEW YORK.

DESIGN FOR A MEGAPHONE.

Application filed December 8, 1924. Serial No. 11,624. Term of patent 3½ years.

To all whom it may concern:

Be it known that I, EUGENE W. SKINNER, a citizen of the United States of America, residing at Fulton, county of Oswego, and State of New York, have invented a new, original, and ornamental Design for a Megaphone, of which the following is a specification, reference being had to the accompanying drawings, forming part hereof.

The figure is a side elevation of a megaphone embodying my new design.

I claim:

The ornamental design for a megaphone, substantially as shown.

EUGENE W. SKINNER.
